CLAIM

The ornamental design for a triangular paint brush, as shown and described.

DESCRIPTION

FIG. 1 is a perspective view of a triangular paint brush showing our new design;

FIG. 2 is a top plan view thereof; and,

FIG. 3 is a side elevation view thereof.

The broken lines showing a handle and a portion of the ferrule and bristles are for illustrative purposes only and the broken lines immediately adjacent the surface shading on the ferrule and those immediately adjacent the ends of the bristles represent the bounds of the claim. None of the broken lines form part of the claimed design.
